UNITED STATES PATENT OFFICE.

ELWOOD GRISSINGER, OF BUFFALO, NEW YORK.

APPARATUS FOR REPRODUCING, AMPLIFYING, AND PROJECTING SOUND WAVES.

Application filed May 11, 1920. Serial No. 380,492.

To all whom it may concern:

Be it known that I, ELWOOD GRISSINGER, a citizen of the United States, and resident of Buffalo, in the county of Erie and State of New York, have invented certain new and useful Improvements in Apparatus for Reproducing, Amplifying, and Projecting Sound Waves, of which the following is a specification.

- 10 My present invention includes a new feature which concerns the reproducing process as a whole, starting with the stylus needle, lever and diaphragm which vibrate the air in the sound box, and including propagation 15 of the sound waves into, through and out of the tone arm and amplifying projector into the open air. It includes utilizing a reproducer having certain qualities explained in my Patents Numbers 1,339,648; 1,339,649; 20 and 1,339,558, in combination with a sound projector having special qualities attainable most readily by employing a reflecting amplifier and projector of the type disclosed in my prior applications Serial Nos. 298,846 25 and 305,601, preferably one with the sonorous plate reflectors arranged as shown in Figure 2 of said latter application, but preferably with certain modifications and improvements described hereafter.
- 30 It is characteristic of the reproducers of said applications that the levers are of rigid construction, are pivoted for movement about a rigidly fixed axis, and are associated with spring elements (wires) so arranged that although the spring tension of said elements is considerable, they afford but slight resilient opposition to oscillatory movements of the lever. When such a lever so mounted is associated with a diaphragm 35 of suitable size and sufficiently flexible the vibratory system as a whole has a low free period of natural vibration.

40 I have discovered that reproducers having a low free period, that is lower than the average of speech frequencies, have not heretofore come into general commercial use although they reproduce sounds with a much smoother and more musical quality than the Victor, Columbia, Edison and other standard 45 commercial reproducers. The reason for this seems to be that the present day art was developed mainly by accepting Victor quality as standard and it is characteristic of Victor reproduction that the reproducer 50 is constructed and adjusted to have a high

free period whereby the quality of the reproduced sound has a noticeably shrill or "brilliant" quality. Originally this reproducer was used in connection with the old-fashioned conical brass horn which contributed a further brilliant effect to the quality of the reproduction. Consequently, when the trade began to pay attention to quality, it became the practice to mellow and dull the metallic brilliancy of the reproduction by the use of long, low-frequency, wooden projectors, as variously embodied in phonographs of the "cabinet" type. The modified quality of reproduction afforded by this combination of high frequency, brilliant reproducer with voluminous, low-frequency projector became in turn a well-known and generally accepted standard for reproduction. The result of using a low free period reproducer in combination with such a long low frequency projector, is to muffle the sound and make it seem to originate at a remote point, far back in the projector. I have further discovered that where the low free period reproducer is combined with a relatively short, high frequency projector, particularly where the projection of the sound is by reflection in accordance with the principles explained in my said prior applications, the smooth quality and the perfect reproduction of overtones characteristic of such low free period reproducers, is combined with a louder more brilliant effect and appears to originate from a point in advance of the mouth of the projector instead of somewhere way back in the depths thereof.

55 My invention also includes certain improvements in the sonorous reflecting projectors which are particularly adapted for employment in combination with low frequency reproducers, though they may be also used in connection with the ordinary standard reproducers now on the market. As described in my prior application, the consonant reflecting plate preferably consists of a sheet or thin plate of sound sensitive material such as the wood used for piano sounding boards, rigidly secured to a rigid frame around the entire periphery of the plate. As contrasted with this, my present invention involves clamping the plates to the frames at two opposite edges and slightly recessing the frame beneath the other two opposite edges so as to leave

these edges of the plate perfectly free for vibration of maximum attainable amplitude, without danger of contacting with anything. The latter construction has very 5 important advantages. The plate can be arranged with its clamped insensitive edges joining the side walls so that only the free vibratory edges extend crosswise in the path of the waves to be reflected, thus making 10 the active reflecting area uniformly elastic lengthwise of the projector instead of having it crossed by non-vibratory clamped zones which are unavoidable where the crosswise edges of the plates are clamped as 15 in my prior devices of this type. In the case of plates formed with diverging sides the tendency to omniperiodic resonant reinforcement of the sound is improved because there is less constraint on the plate 20 and it can vibrate more like a set of parallel strings.

Also, a given plate of given thickness, clamped only at two opposite edges, is much 25 more flexible and sensitive and has a lower natural frequency than when clamped about its entire periphery. Hence, plates of minimum permissible thinness may be mounted so as to be more sensitive; also in selecting plates so as to get a desired range of frequencies, or to get a desired ratio between 30 the wave reflecting quality and the wave absorptive and reradiating quality, the plate can be thicker and more substantial than would otherwise be possible.

Moreover, a plate clamped about its entire periphery tends to act somewhat like a diaphragm with reference to its overtone or segmental vibrations, that is to say, its segmental vibrations are not harmonics of 35 its fundamental but are discordant with said fundamental and with each other. When the plates are clamped only at two opposite edges, however, their segmental vibrations tend to follow more nearly the harmonic law characteristic of stretched strings, that is to say, when vibrated by a note corresponding to one of their natural 40 frequencies either fundamental or harmonic, the other natural frequencies excited thereby are harmonious and pleasing instead of discordant.

By proper coordination of the various features of my invention so as to take full advantage of my above described discoveries, sound effects are attainable which are entirely unique as to the loudness, vividness and perfect quality of the reproduced sounds.

From the above explanation, it will be 60 evident that in its broader aspect, my invention consists of combining a reproducer of low free period with a relatively short or high frequency projector and as a preferable embodiment, emitting the sound by reflection, preferably from plates affording

a desired degree of consonant re-enforcement.

The above and other features of my invention may be more fully understood from the following description of an illustrative 70 embodiment thereof shown in the accompanying drawings, in which

Figure 1 is a vertical section of a phonograph cabinet of ordinary construction having my improved apparatus embodied therein;

Figure 2 is a detail plan view partly in section on the line 2—2, Figure 1;

Figure 3 is a front elevation of the projector looking into the mouth thereof, the 80 cabinet being broken away to show the construction more clearly;

Figure 4 is a detail perspective of one of the sonorous plate elements with a portion of the plate broken away to show the frame 85 more clearly;

Figure 5 is a detail view showing a corner joint where a sonorous plate element and its frame are secured to the side wall of 90 the projector;

Figure 6 is a vertical section of a projector like Figure 1 with an added feature, the section being indicated by the line 6—6, on Figure 7;

Figure 7 is a horizontal section on the 95 line 7—7, Figure 6; and

Figure 8 is a front elevation looking into the mouth of the projector shown in Figures 6 and 7.

In Figure 1 the various parts of a cabinet phonograph are conventionally indicated. The case 1, has a cover 2, enclosing a shallow cavity 3, having a bottom 4, supporting the phonograph motor case 5, the rotary support 6 for the record, the tone arm swivel 8 and tone arm 9, all of which may be of any known or desired construction.

The reproducer 10 preferably has the low frequency characteristics referred to above 110 and more fully explained in my prior applications, the stylus lever being rigid, the mounting and tensioning devices therefor having slight resilient effect as against oscillatory movement of the lever and the diaphragm being comparatively large and flexible. Any other construction adapted to afford the desired low frequency characteristics for the reproducer, may be employed.

Communicating with the lower end of the tone arm is the upper end 11 of the tubular conduit 12 leading to the reflecting projector. This conduit has the form of a frustum of a pyramid curved rearwardly 125 and diverging laterally so that at the lower end, where it joins the reflecting projector, it is only a little less than the full width of the latter. This expansion passage is preferably of gray cast iron with its walls 130

about $\frac{1}{8}$ inch thick so that, acoustically considered, it forms a natural extension of the sound conducting passage afforded by the tone arm 9.

5 The sound waves which are propagated from the lower end of conduit 11 impinge upon the sonorous reflecting plate 13 at a high angle. As shown, this angle is 45° for most of the wave front though somewhat less than this for the part that spreads downward from the lower flank of the sound "beam".

10 The construction and mounting of this reflecting plate 13 is indicated in the various figures but is shown more clearly in Figures 4 and 5. The mounting comprises the very substantially rigid frame 20 which may be of spruce $\frac{3}{4}$ inch wide by half an inch thick, or if of metal, may be of less cross section. The side faces at 21, 21 are preferably smoothly finished so as to lie in exactly the same plane. To these faces are secured the sensitive plate 13, by screws 22 arranged at short intervals. The heads of 15 these screws preferably have flat under surfaces to engage squarely with the top surface of plate 13, so as to clamp the same as rigidly as possible. The two other side members of the frame are recessed at 23 so as to give a clearance for the adjacent free edges of the vibratory plate 13. The recessing is preferably as shallow as the purpose 20 will permit, $\frac{3}{16}$ of an inch being usually sufficient. In assembling the reflecting plates 25 with the other members of the projector, care is taken to secure a rigid clamping contact applying symmetrical pressure to the plate 13 at exactly corresponding points on the upper and lower surfaces thereof, as 30 shown at 24, 25, Figure 5. I find that this precaution is very important as contributing to proper reaction of the plates with reference to the waves impinging thereon.

35 In assembling the plates in the projector, it is important to arrange the clamped edges of the plates at the sides of the projector and to have the free edges extending transversely. As indicated in Figure 1, the assembly is such as to leave the unclamped edges of the plates free of any possible vibratory contact with adjacent elements and where two plates come together as at the lower right hand corner in Figure 1, it is desirable to have one plate as 13 extended past the free edge of the adjacent plate. The 40 uniform spacing of plate 13 is clearly indicated at 18, Figure 1.

45 The side walls 16 of the projector may be of solid spruce, $\frac{1}{2}$ to $\frac{5}{8}$ inch in thickness or they may be of metal or if desired, they may be of the same resonant plate construction as above described with reference to plate 13.

50 Preferably, the reflector 13 is vertical and the waves reflected therefrom at a 45° angle

impinge upon a second reflector 14 whence they are reflected upward and out of the projector at a 45° angle.

55 After the second or final reflection of the sound "beam" from the bottom plate 14, it 70 travels approximately parallel with a third sound sensitive plate 15 which serves to hold the upper flank of the beam from lateral diffusion while the lower flank thereof is free to diffuse toward horizontal and downward directions by following its natural tendency to spread spherically in all directions. This 75 seems to give the best possible distribution for listeners in an ordinary room when the mouth of the projector is at the usual level of three to four feet from the floor.

80 It will be understood that the "sound beam" is subject to spherical diffusion wherever its lateral flanks are not guided and confined and that such diffusion tends to 85 occur inside of the projector as well as outside but such flank diffusion is proportional to the density of the compressions and rarefactions in the individual waves, and this 90 density is enormously decreased by the expansion effected in the passage 12 which may have an area of say three square inches at the upper end expanding to say twenty square inches at the lower end. Moreover, 95 the main reflections are only two in number, and the exposed flanks are short so that opportunities for objectionable diffusion effects are minimized and such diffusion as there is has a fairly direct path outward 100 through the mouth of the horn. This fact is 105 evidenced in practice by the remarkable clearness and vividness of quality of the projected sound.

110 As explained in my prior applications, the reflecting plates are preferably of such quality and thinness that they will cause resonant reinforcement of the sound and will vibrate responsively thereto. Any vibrations thus set up in the plates cause them to be sources of re-radiated energy propagated at right angles to the surface of the plate. Any such waves generated by plate 13 are mostly 115 propagated directly out of the mouth of the projector. Similar waves re-radiated from 120 plate 14 will mostly impinge upon reflector 15 and be reflected out of the projector along lines parallel with the radiation from plate 13.

125 During propagation through the reflecting projector, the sound waves are permitted to expand laterally at a rate somewhat more rapid than in the expansion passage 12, the divergence of the side walls 16 of the projector being nearly an inch laterally for each inch measured along the axis of the projector, as may be seen by reference to Figures 2 and 3. Thus the expansion is progressive from the point where the waves enter the expanding passage at 11 to the mouth of the projector where they emerge 130 into the open air.

The above described parts are organized so as to afford the above described graduated expansion of the wave front and application thereof to the outside air over a large area, combined with a desired minimum for the distance of travel of the waves during such expansion. To this end, the tone arm is pivoted at the front of the cabinet almost directly over the outlet instead of being pivoted in the rear as is now common practice in commercial devices of this type. This makes it desirable to slant the reproducer stylus toward the pivotal point of the tone arm instead of away from it because this arrangement permits the operator to use his right hand for manipulation of the box to pivot it to and from the record and to renew the stylus needles.

By this location of the tone arm, the length required for the reflecting projector is reduced to about half that shown in my prior applications. In this connection, it is to be remembered that physical dimensions as well as proportions are of considerable importance where amplifying and resonance effects are to be produced on sound waves, because the functioning of such devices are intimately related with the physical lengths of the waves to be amplified thereby. Hence, while very wide latitude is permissible, some notion of desirable sizes is necessary. In my preferred apparatus, the rear sensitive plate 13 may be nearly square or say 8 inches high by 7 inches wide, the sound beam projected thereon being of slightly less width say 6 inches by 3½ inches. The bottom plate 14 will be of the same width at the rear as plate 13; will be say 8 or 9 inches from rear to front, and will be about 15 or 16 inches wide, at the front. The dimensions of plate 16 will be those required for a 45° plate to fit the dimensions previously given, and the vertical height of the outlet opening determined thereby may be say 9 or 10 inches.

The amplifying projector is thus only about 8 or 9 inches deep from front to rear. This is the physical length of a quarter wave of a note of about 350 frequency. It is also the three-quarter length of the wave of a note of somewhat over 1000 frequency. Hence, while the proportions and shape of this cavity are not such as to promote very sharp air column resonance for any frequency, and while the wide mouth tends to make the air cavity more or less omniperiodic, it is important to note that the periodicities which it ought to reinforce most strongly include substantially the entire range of important speech frequencies. Moreover, for such reinforcement, the stationary air waves established by reflection from the mouth of the projector back to the rear wall 13, will never have to be over three-quarters of a wave for the higher fre-

quencies, and for certain of the important lower frequencies will be only one-quarter of a wave.

If the projector be somewhat deeper than this, say 12 inches from front to rear as 70 is sometimes desirable where the lateral flare of the walls is not so extreme, its characteristics so far as concerns quarter wave length, will extend down to and include frequencies of say 275 to 250, without lowering the 75 three-quarter wave length situation below the frequencies lying between 900 and 1000 and hence not below the uppermost of the vowel sounds. Any pronounced air column resonance for frequencies lower than 250 or 80 even 350 is sufficient since the lower frequencies are not so subject to attenuation as the higher ones and they are sufficiently preserved and amplified by the "sounding board" effect of the walls of the projector. 85

While I do not wish to be considered as limiting my invention or making it in any wise depending upon the correctness of the theories above advanced, it is evident that they seem to fit the facts; that they tend to 90 account for the remarkable results achieved and that they afford an intelligent basis to work from in practicing my invention and in devising desirable modifications thereof.

Another feature of my invention which 95 apparently contributes to the new results attained, is the employment of rolled sheet aluminum for the plates. These are preferably about 16 to 22 gauge. Such plates, though relatively thick and stiff, seem to be 100 flexible enough and sensitive enough when clamped at the side edges only. They seem to be of advantage for my present purpose because they apparently reflect a large percentage of the energy and such part of the 105 energy as is expended in causing resonant vibration of the plates is re-radiated with very small loss due to the dense nature of the material of the plates and the small internal friction. They seem not to use up 110 and dissipate energy to anything like the extent that thin wooden plates do, even when the latter are of most carefully selected and finished material.

Figures 6, 7 and 8 show the projector 115 substantially as described above but having the added feature of diverging partition plates 19, 19 arranged opposite to and preferably parallel with the side walls 16. These plates are held in position by transverse rods 30, 31 secured through the wide walls by clamping nuts 32. The partition members are threaded on these rods and are secured in position by clamping nuts 33, 33. It will be noted that these partition members extend rearward about half the depth of the reflecting projector and are supported by the rods 30, 31 in position to barely clear the sensitive reflecting plates 14, 15.

Preferably the partition plates are sensi- 130

tive plates of the same kind and mounting as above described for plates 13, 14 and 15. The clamped edges being arranged at top and bottom and the free vibratory edges 5 transverse to the direction of propagation of the waves.

I claim:

1. A sound amplifier including a primary expansion conduit having an oblong outlet, 10 and a projector portion comprising reflecting wall at an angle of approximately 45 degrees to said outlet, a second reflecting wall immediately adjacent and approximately at right angles to the first and extending 15 approximately to the exit plane or mouth of said projector portion, and a wall opposite said second reflector, approximately parallel with and out of the path of the main sound beam reflected from said second reflector.

2. A sound amplifier comprising a primary conduit having walls diverging in one dimension more than in the other and a projector portion having walls diverging mainly in said other dimension, said projector portion being characterized by two reflecting walls immediately adjacent each other on the same side of the device, one reflector being in receiving relation to the beam from said primary conduit and the 25 second reflector being in receiving relation to the first and extending approximately to the exit plane of the mouth of said projector so that the main beam from the second reflector is projected directly across said 30 plane into the outer air.

Signed at New York city in the county of New York and State of New York this tenth day of May A. D. 1920.

ELWOOD GRISSINGER.
